UNITED STATES PATENT OFFICE.

WILLIAM BARTHOLOMAE, OF BROOKLYN, NEW YORK.

MUSICAL INSTRUMENT.

Application filed January 6, 1926. Serial No. 79,643.

This invention relates to a musical instrument and has for an object to provide a construction which may be used as an instrument for playing tunes or may be used as a toy, the construction being such that an experienced or inexperienced person may secure desirable results therefrom.

Another object of the invention is to provide a musical instrument wherein a single vibratile or sounding member is provided with means for changing the pitch as the instrument is operated.

Another object of the invention is to provide a musical instrument wherein one hand is used to change the pitch and the other to produce the mechanical movements necessary to cause sounds.

In the accompanying drawing—

Figure 1 is a perspective view of a preferred embodiment of the invention.

Figure 2 is a longitudinal vertical sectional view through Figure 1, approximately on line 2—2.

Figure 3 is a transverse sectional view through Figure 2, approximately on line 3—3.

Figure 4 is a fragmentary horizontal sectional view through Figure 2 on line 4—4.

Figure 5 is an enlarged fragmentary sectional view through Figure 2 on line 5—5.

Referring to the accompanying drawing by numerals, 1 indicates a casing or frame which may be of metal, wood or other desired material and which if desired, may be provided with supporting legs 2 and 3. These legs are removably connected with the frame 1 and may be used in connection therewith or the frame 1 and associated parts may be used independently of the legs. 40 When the device is on a table or similar support, the legs are used as shown in Figure 1 but when the device is used in the lap, the legs may be dispensed with.

As indicated in Figure 4, the frame 1 is provided with side members 4 and 5. Each of these side members is provided with an inner section 6 preferably of wood and an outer section or side plate 7 preferably of metal. Each of the inner sections 6 is provided with a slot 8 at one end accommodating the rod 9 while at the opposite end of the frame the members 6 are provided with bores for receiving the ends of the rod 10, said rod, however, not projecting through 55 the side plates 7. The rods 9 and 10 may be metal, wood or other desired material and

are each provided with a slit 11 for receiving the respective ends 12 and 13 of the vibratile member 14. The member 14 when caused to vibrate, will produce a sound and

by shifting rod 9 longitudinally of frame 1, the vibratile member 14 will be bowed as indicated in dotted lines in Figure 2 whereupon a different pitch is produced when the ball or knob 15 strikes the same. It will

be noted that both the rods 9 and 10 are rocked simultaneously and rod 9 will move longitudinally of the slots 8 as the member 14 bows. U-shaped arms 16 and 17 are connected in any suitable manner with the rods

9 and 10 and these arms are connected together by a flexible member 18. The member 18 has been shown as a flexible strip of metal though it might be cord or other flexible member so that when it is pressed downwardly at any point between its ends, the arms 16 and 17 will be swung inwardly for

rocking rods 9 and 10. An indicating arm or pointer 19 is rigidly secured to the ends of rod 9 and extends to a point exteriorly of the frame 1 so that the free end may pass over the scale dial 20. When member 18 is depressed as shown in dotted lines in Figure 2, the pointer 19 will move upwardly, as for instance, to the position indicating G

85 on scale 20. If the member 18 is forced down a short distance further, the pointer will move to A on scale 20 whereas if it is released somewhat, the pointer will move back to F. When the pointer moves back

90 and forth as just described, the vibratile member 14 will be bowed to a greater or less extent and will produce sounds indicated by the letters on scale 20. By this construction and arrangement, a tune may be readily played on the actuation of the ball 15. The ball 15 is connected to a flexible member 21 which is preferably a thin strip of steel secured at one end to the bar

22, which bar is pivotally mounted at 23 in 100 the frame 1. The frame 1 is cut away so as to admit the bar 22 and is provided with a shoulder 24 against which bar 22 presses when the outer end 25 of the bar is depressed manually. Preferably, the parts are

105 so positioned that the bar 22 engages the shoulder 24 and the ball 15 will not contact with the vibratile member 14 unless the same is given a quick movement. In this way when the bar 20 is struck and raised until it 110 strikes the shoulder 24, ball 15 will quickly strike the vibratile member 14 and will move

away from the same so that a proper sound may be secured. In order to play a given musical composition, a music rack 26 is provided for holding a suitable sheet of music 5 27, said rack having a body 28 and a pressed out tongue 29 adapted to pinch the music sheet 27. The lower end of the rack 26 is bent back on itself at 30 so as to form a groove or channel for accommodating the 10 turned over portion 31 of one of the metal side pieces 7.

In operation, when it is desired to use the device, the operator places one hand or a finger on member 18 and the other on the 15 end 25 of bar 22. If the lowest note is desired, end 25 may be struck by the hand for causing the ball 15 to strike the member 14 and thereby secure the desired sound. In order to change from one note to another, 20 member 18 is pressed downwardly or released to a greater or less extent for bowing to a greater or less extent member 14. Upon each change ball 15 is caused to function and a sound will be produced thereby. A person 25 operating the device may watch the pointer 19 in order to secure the proper note or may after some practice, operate the device through the touch. When used by a child as a toy, the member 18 and member 20 are 30 both moved more or less promiscuously in order to secure different tones as member 14 is bowed. It will be noted that by bowing the member 14, the same is put under greater or less tension according to the position of 35 the rod 9 and the higher the tension the higher the note. The ball 15, flexible member 21 and the swinging bar 22 have been shown as means for striking the vibratile member but if desired, an independent hammer 40 might be used and under some circumstances, a double hammer might be used connected to the U-shaped support whereby the vibratile member could be struck on both sides.

45 What I claim is:

1. A musical instrument, comprising a

vibratile member, a rockable rod connected to said vibratile member at each end, manually actuated means for rocking said rods, one of said rods being movable toward the 50 other as it is rocked, and a manually actuated striking member for striking said vibratile member.

2. A musical instrument comprising a frame, a pair of rods rotatably mounted in 55 the frame, one of said rods being also capable of longitudinal movement, a flat vibratile member of the same width throughout positioned so that one end will project into each of said rods, manually actuated means for 60 rocking said rods so as to vary the tension of said vibratile member, and a swinging member for striking said vibratile member in order to produce sound.

3. A musical instrument comprising a vi- 65 bratile member, a manually actuated structure for bringing said vibratile member under tension, said manually actuated structure acting simultaneously on both ends of said vibratile member, and a pivotally 70 mounted manually actuated striking member, said striking member being formed with a bar, a ball and a spring for supporting said ball, said ball being positioned to strike said vibratile member.

4. A musical instrument comprising a frame, a pair of rods rotatably mounted in the frame, one of said rods being also capable of movement longitudinally of the frame, a vibratile member having one end connected 80 to the rod capable of movement longitudinally of the frame and the other end connected to the other of said rods, an arm connected with each of said rods, a flexible member connected with both of said arms whereby when the same is pulled in a direction 85 away from said vibratile member the arms will be swung and cause said vibratile member to bow, and means for striking said vibratile member for causing the same to produce a sound.

WILLIAM BARTHOLOMAE.
